(57) **CLAIM**

I claim the ornamental design for a wine aerator, as shown and described.

DESCRIPTION

FIG. 1 is a top perspective view of the wine aerator;
 FIG. 2 is a bottom perspective view of the wine aerator;
 FIG. 3 is a top view of the wine aerator;
 FIG. 4 is a bottom view of the wine aerator;
 FIG. 5 is a left view of the wine aerator;
 FIG. 6 is a right view of the wine aerator;
 FIG. 7 is a front view of the wine aerator; and,
 FIG. 8 is a back view of the wine aerator.
